United States Patent Office.

R. M. MANSUR, OF AUGUSTA, MAINE.

Letters Patent No. 79,242, dated June 23, 1868.

IMPROVED CARPET-STRETCHER AND TACK-HOLDER.

The Schedule referred to in these Letters Patent and making part of the same.

TO WHOM IT MAY CONCERN:

Be it known that I, R. M. MANSUR, of Augusta, in the county of Kennebec, in the State of Maine, have invented a new and useful Improvement in Carpet-Stretchers and Tack-Holders; and I do hereby declare that the following is a full, clear, and exact description of the same, reference being had to the annexed drawings, making a part of this specification, in which—

Figure 1 is a perspective view, and

Figure 2 a sectional view of the same.

In fig. 1, A refers to a malleable-iron or composition plate; B, a wooden handle for the same; C, the serrated prongs of the plate; D D, notches for extracting tacks; E E, elastic rubber bands, to assist in holding the tacks in place.

In fig. 2, A, the three-pronged serrated plate; F F, little notches in the middle prong of the plate, for holding the tacks which are to be driven; E E, the elastic rubber bands, which assist in holding the tacks in place by pressure against them.

To use this instrument or article, the handle is taken in the left hand, placing a tack in each of the notches before described, which is kept in an upright position in place, by the pressure of the elastic band or bands E E, when, by pressing against the edge of the carpet with the serrated plate, it is pushed into place; then, by striking on one of the tacks with a hammer, (or both tacks, if it is wished to put in two so near together,) it holds the carpet in place, when the tool may be drawn away from the tack or tacks, and the tack or tacks driven in further if wished. The same operation to be repeated as near as it is wished to have the carpet fastened.

The advantage of this improvement is, the doing away with springs and jointed plates, which are liable to get out of order, and there being two notches or places for placing the tacks, the work can be done faster. The plate being in one piece, it is less complicated, can be made cheaper, and stronger for taking out tacks. Should the elastic bands become worn after considerable use, they can be turned on the prongs. There should be a recess in the prongs, the sides, and underneath, for the rubber rings to rest in to keep them in place. If preferred, the little notches can be filed in the inside of the two outside prongs, and only one elastic rubber ring used on the middle prong of the serrated plate, or it can be made with only two prongs, a rubber on one or both, and only one tack used at a time, it being put in the middle of the plate, held in place by the rubber ring or rings.

I disclaim the serrated plate A, and the extracting notches D D; but

What I claim, and desire to obtain by Letters Patent, is—

The construction of the three-pronged plate, with the elastic rubber rings F F, as a tool for the purposes set forth and herein described.

R. M. MANSUR.
